United States Patent Office.

PELEG BARKER, OF BATTLE CREEK, MICHIGAN.

Letters Patent No. 77,158, dated April 28, 1868.

IMPROVEMENT IN LATHES FOR CUTTING IRREGULAR FORMS.

The Schedule referred to in these Letters Patent and making part of the same.

TO WHOM IT MAY CONCERN:

Know all men that I, PELEG BARKER, of the city of Battle Creek, in the county of Calhoun, and State of Michigan, have invented a new and useful Improvement in an Improved Apparatus for Fluting Furniture, Columns, or any other articles, and for chamfering frames for machinery or agricultural implements, or sticks of wood for any other purpose, and for hollowing staves and wood for other purposes; and do declare that the following is a true and accurate description thereof, reference being had to the accompanying drawings, and to the letters of reference marked thereon, and being a part of these specifications.

The nature of this invention is so to construct a machine for fluting, chamfering, and hollowing purposes, that it can be used across instead of with the grain of the wood, with curved or bowed knives or cutters.

The accompanying drawing is a very faithful representation of my apparatus.

A is a frame, upon which is placed the mandrel B, having attached to its outer ends the curved or bow-shaped knives or cutters C C', the mandrel being driven by a proper belt running upon the pulley D. A guide-rest, E, is placed in front and diagonal with the cutter-face plate F, and so arranged as to allow the cutter to pass through the edge of the guide-rest in its downward motion, thereby chamfering or cutting the timber transversely with the grain.

The back end of the ways, near the cutter, is placed further from the cutter, allowing it to clear and not cut the timber in its upward motion. Various forms and shapes of ways may be substituted, so that any desired angle may be obtained.

The sliding frame G is placed under and inclined from the outer to the inner end of the mandrel, secured and adjusted by the ways H, and is provided with a centre-point inside, at its lower end, at its opposite and upper end, with centre-point at the inner end of the screw J, which is operated by the lever K.

The division-plate L is placed upon and back of the centre-point on the screw J, and rotating freely upon it, and is held in position by the collar M, preventing it from sliding back, and holding it firmly in its place. The plate is provided with proper spurs, which pierce the end of the wood, (the other end being secured in its position by the centre-point at the opposite and lower end.) The plate is held in position by the rod N, passing through the framework, to and through proper holes in the plate.

The diagonal relation of the way J with the mandrel admits of a small cutter, allowing the wood being operated upon to pass under the pulley.

The leg or column to be fluted, or stave to be hollowed, is placed in said sliding frame G, secured by said points, the plate L, provided with the spurs and the rod N, the whole moving under the cutter C on the ways H, which are supported on inclined planes, allowing the same to be elevated or depressed, according to the size of the column or stick to be fluted or hollowed.

What I claim as my invention, and desire to secure by Letters Patent, is—

The sliding adjustable frame G, containing the holding-devices for the uncut timber, arranged relatively with the curved knife C, when constructed and operating as described.

PELEG BARKER.
